UNITED STATES PATENT OFFICE

ANTONIO IMPELLITTERI, OF NEW LONDON, CONNECTICUT

NONREFILLABLE BOTTLE

Application filed May 18, 1927. Serial No. 192,174.

The invention relates to nonrefillable bottles, and has for its object to provide a device of this character, the stopper of which is provided with a double valve seat with which a reciprocating valve cooperates in a manner whereby liquid will be allowed to pass from the bottle during a pouring operation by the unseating of the valve with one of the valve seats, the liquid allowed to pass around the valve through discharge ports in the other valve seat, and spring means for maintaining the valve out of engagement with the last named valve seat during the pouring operation. The spring means is strong enough to prevent the seating of the valve during a pouring operation, but not strong enough to prevent the unseating of the valve upon inverting the bottle where the weight of the liquid will be on the valve. A further object is to provide a nonrefillable bottle stopper comprising a body member having a slidable tubular member therein and terminating in a double valve, which double valve cooperates with adjacent valve seats in a manner whereby upon inverting the bottle the weight of the liquid will unseat the valve in relation to the lower or inner valve seat, thereby allowing the liquid to pass around the valve and through discharge ports in the outer valve seat. Also to provide spring means cooperating with the valve and preventing the seating of the valve on the outer valve seat during a pouring operation and forming means whereby upon fraudulent attempts to fill the bottle under a vacuum or pulsation, the valve will be seated. A further object is to provide the stopper with outwardly converging discharge ports positioned whereby when an instrument is inserted through said port for manipulating the valve, said valve will be in the path of the instrument and will immediately seat. A further object is to provide a locking ring for holding the stopper in the bottle neck, which ring is an expandable split one, and when the stopper is forced into the bottle neck, expands outwardly into a channel in the inner periphery of the bottle neck,

thereby positively locking the stopper in the bottle neck.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a vertical transverse sectional view through a conventional form of bottle and the stopper.

Figure 2 is a horizontal sectional view taken on line 2-2 of Figure 1.

Figure 3 is a horizontal sectional view taken on line 3-3 of Figure 1.

Figure 4 is a horizontal sectional view taken on line 4-4 of Figure 1.

Referring to the drawing the numeral 1 designates a conventional form of bottle, and 2 the neck thereof. Disposed within the neck 2 is a stopper 3, which stopper is provided with a flange 4, which engages the upper end of the neck and is held within the neck 2 by means of the split expandable ring 5, which ring engages in the channel 6 in the outer periphery of the stopper and into the channel 7 in the inner periphery of the neck 2. It will be noted that the channel 6 is relatively deep whereby the ring 5 may be contracted therein so that the stopper will pass into the neck as well as the ring, and after the flange 4 comes into engagement with the upper end of the neck 2, the channels 6 and 7 will be in the same plane, and at which time the ring 5 will expand outwardly to a position as shown in Figure 1, where it will be within both channels 6 and 7, thereby positively locking the stopper in the bottle neck. The lower outer periphery of the stopper 3 is preferably provided with

an annular cork member 8 for forming a close water tight fit of the stopper, consequently preventing leakage or evaporation.

Slidably mounted in the aperture 9 extending through the cork or stopper body 1 is a tubular member 11, through which liquid

passes and the opposite sides of said tubular member adjacent its upper end is provided with discharge ports 12, through which liquid passes, when the bottle is inverted for a pouring operation. The upper or outer end of the tubular member 11 terminates in a valve 13 which valve is a double one, and when the bottle is not in use, or when it is under pressure or impelled for fraudulent filling the portion 14 thereof engages the valve seat 15, and where it is under a suction for filling the valve 13 moves to a position where its portion 16 will engage the valve seat 17, thereby preventing flow of liquid into the bottle through the diverging ports 18, therefore it will be seen that the bottle can not be filled under normal conditions. Disposed within the member 20 which is held within the outer end of the stopper by crimping at 21 is a coiled spring 22, and which coiled spring is of sufficient expansive strength to normally maintain the valve 13 out of engagement with the valve seat 13 during a pouring operation, and the weight of the fluid serves to unseat the valve 13 from the seat 15 a sufficient distance to allow the liquid which passes through the tubular member 11, ports 12, to pass around the valve 13, and through the discharge ports 18. Threaded on the upper end of the stopper member 20 is a cap 23, which cap is provided with a needle valve 24, and which needle valve, when the cap 23 is tightened, cooperates with the upper end of the member 20 and forms a closure for the upper end of the ports 18 where they converge together, therefore it will be seen that evaporation of the liquid will be reduced to a minimum.

From the above it will be seen that a non-refillable bottle stopper is provided, which is simple in construction, and one wherein a double valve cooperating with adjacent valve seats is utilized in a manner whereby liquid may flow from the bottle through the stopper and around the valve when said valve is unseated; in relation to both of the valve seats, and upon attempts to fill the bottle by a pouring operation, the valve will seat, and if an attempt is made to fill by exhausting the air or pulsations, the valve will also seat, by overcoming the tension of the coiled spring 22.

The invention having been set forth what is claimed as new and useful is:—

A non-refillable bottle stopper comprising a body member adapted to be received in the neck of a bottle, an axially movable valve sleeve slidably mounted in the body member and having a longitudinal chamber therein and ports extending through the sleeve at opposite sides thereof adjacent its outer end, said body member adjacent the outer end of the sleeve being provided with a chamber, said chamber adjacent the sleeve being of greater diameter than the sleeve and of less

diameter than the other portion of the chamber, a valve seat between the two diameters of the chamber, a valve carried by the sleeve and cooperating with the seat, a plug in the chamber of the body member above the valve in spaced relation thereto and having upwardly and inwardly converging and connecting discharge ports, an extension carried by said valve and slidably mounted in a chamber between the inner ends of the discharge ports and a spring cooperating with said extension and forming means for maintaining the valve seated during the non-pouring operation.

In testimony whereof I hereunto affix my signature.

ANTONIO IMPELLITTERI.
